ILLUMINATING COMPACT

Max Aronek, New York, N. Y.

Application October 23, 1944, Serial No. 559,924

3 Claims. (Cl. 240—6.45)

This invention relates to a compact for powder or other cosmetic accessories and has for its primary object the provision of such a compact arranged to accommodate a battery and bulb to illuminate the user's face and so organized as to be capable of manufacture and assembly at a minimum cost.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the accompanying drawing Fig. 1 is a perspective view of the preferred form of compact according to the invention, it being shown open, Fig. 2 is a section through the compact when closed, the section being as on the line 2—2 of Fig. 1, Fig. 3 is a bottom plan view of the interior elements, and Fig. 4 is a broken-out sectional view on the line 4—4 of Fig. 3.

The compact comprises a container or shallow box 1 having a hinged cover 2 in which is suitably secured a mirror 3.

The mouth of the container is substantially closed by a partition 4 having depending side and end walls 5 closely fitting within the container walls and dimensioned to space the partition from the bottom of the container, as shown.

Intermediate its ends the partition is formed with one or more wells, such as 6 and 7, to receive powder, puff or the like; and adjacent its ends the partition is provided with raised wall portions. Thus, at the front end, the partition is slit and bent upwardly, as at 8, to form a reflector for a bulb 9 mounted in the compartment or space directly beneath the reflector. And at its other or rear end the partition is raised, as at 10, to form the upper wall of a compartment, to receive one or more batteries 11, 11'. As shown, the raised portion 10 may be in the form of a battery compartment cover, hinged at 12, to provide ready access to the battery or batteries for replacement.

Directly beneath the wells 6 and 7 and terminating short of the bulb and battery compartments is an insulating member 13 in the underside of which is a recess 14 in which is slidably mounted a switch contact member 15. The contact member is supported by a stud 16 which extends up through suitable slots in the insulating member and partition and terminates in an operating button 17 on the upper side of the partition.

Secured to the underside of the insulating member 13 are conductor members arranged to pass from the battery compartment, to the switch and thence to the bulb compartment. In the arrangement shown, wherein two batteries are illustrated, a bridging conductor piece 18 is also shown as secured to the underside of the insulating member and serving to couple the two batteries in series. From one side of battery 11 a conductor strip 19 passes directly to the bulb compartment wherein it is suitably formed to provide a socket 20 to receive one end of bulb 9. From the opposite side of end of battery 11' a conductor strip 21 passes to the recess 14, terminating therein in a spring contact ear 22. Another conductor strip 23, having a companion contact ear 24 located in recess 14, is secured to the underside of insulating member 14 and extends to the bulb compartment where it terminates in a socket 25 to receive the other end of bulb 9. Thus, as will be understood, the bulb circuit is opened or closed by sliding button 17 back and forth from the illustrated, open circuit to the closed circuit position in which the contact piece 15 bridges the spring ears 22, 24. At 26 is indicated a thin sheet of insulating material laid over the entire bottom of the container 1.

As will be observed, the switch member, comprising contact 15, stud 16 and button 17 serves to unite the partition and insulating member, the whole thus constituting a simple conveniently assembled unit bodily insertable into the container, being secured therein as by the snug fit and resiliency of the depending walls 5, or soldered or otherwise secured as may be preferred.

The cover 2 is, of course, designed to cooperate with the container and contents. If, as shown, the over-all thickness of the major part of the compact is desired to be less than sufficient to accommodate the full thickness of the batteries, the cover is recessed, as at 27, to accommodate the raised wall portion 10 of the partition.

In the light of the foregoing description of the preferred form of the invention, the following is claimed:

- 45 1. In a compact including a container and a cover therefor, the combination of a partition adapted to form a closure for the mouth of the container and having a well formed therein, an insulating member beneath the well, said well and insulating member terminating short of opposite ends of the container to form at such ends, respectively, bulb and battery compartments, a recess in the underside of the insulating member, a switch member slidably mounted in the recess, and conductor members secured to the

underside of the insulating member extending from the battery compartment, to said recess and to the bulb compartment.

2. In a compact including a container and a cover therefor, the combination of a partition adapted to form a closure for the mouth of the container and having a well formed therein, an insulating member beneath the well, the partition having a raised wall portion adjacent one end of the container beyond the well and insulating member forming a battery compartment, and a raised wall portion adjacent the other end of the container to form a bulb compartment and reflector, a recess in the underside of the insulating member, a switch member slidably mounted in the recess, and conductor members secured to the underside of the insulating member extending from the battery compartment,

10
15
ment, to said recess and to the bulb compartment.

3. In a compact including a container and a cover therefor, a unitary insert for the container comprising a partition adapted to form a closure for the mouth of the container and having depending walls fitting within the container walls, said partition having raised wall portions at opposite ends thereof to form respectively, with the container, bulb and battery compartments, an insulating member beneath the partition and terminating short of said compartments, conductor members secured to the insulating member and extending from the battery compartment to the bulb compartment, and switch means extending through and securing against separation the partition and the insulating member.

MAX ARONEK.
